UNITED STATES PATENT OFFICE.

WILSON P. HUNT, OF MOLINE, ILLINOIS, ASSIGNOR TO G. D. REYNOLDS & COMPANY,
OF ROCK ISLAND, ILLINOIS, A FIRM.

SCREW-DRIVING MACHINE.

950,534.

Specification of Letters Patent. Patented Mar. 1, 1910.

Application filed March 30, 1906. Serial No. 309,009.

To all whom it may concern:

Be it known that I, WILSON P. HUNT, a citizen of the United States, and a resident of Moline, in the county of Rock Island and State of Illinois, have invented certain new and useful Improvements in Screw-Driving Machines, of which the following is a clear, full, and exact description.

My invention relates to a screw driving machine, and is designed for use in shops and factories having work in which it is desired to set screws with greater accuracy and rapidity than could possibly be done by hand.

The object of my invention is to feed the screws to the driver from a suitable magazine one by one as rapidly as the ability of the operator makes it necessary, no matter what the size of the screws are, and to prevent the screws being driven into the work so far that the head is buried and the hold of the screw impaired, substantially as hereinafter more fully explained and as particularly pointed out in the claims.

In the drawings:—Figure 1 is a front elevation of my invention with the lower part of the standard of the machine broken away. Fig. 2 is a side elevation of the same. Fig. 3 is a front elevation similar to that shown in Fig. 1, omitting the standard, and showing the magazine, the chuck and the parts on the upper end of the driving shaft in vertical section. Fig. 4 is a plan view thereof. Fig. 5 is a perspective view of one of the jaws that clamp the screws during the insertion of the same into the work, drawn to a larger scale. Fig. 6 is a diagrammatical view showing the several parts of the magazine involved in expelling the screws, with the exception of the annular side-wall and revolving table thereof, slightly separated from their normal assembled position and drawn in perspective. Figs. 7 and 8 show vertical sections of the chuck separated from the machine. Fig. 9 is a perspective view of the tubular filler of said chuck. Fig. 10 is a fragmental detail section taken in a vertical plane at right angles to Fig. 1 through the center of the main operating shafts, and drawn to a larger scale. Fig. 11 is a top plan view of a fragmental portion of the screw-feeding mechanism. Fig. 12 is a vertical section taken on line 12—12 Fig. 11,

and, Fig. 13 is a vertical section thereof taken at right angles to Fig. 12.

55

Referring to the drawings A represents a vertical standard having a suitable table B adjustable vertically thereon. The standard extends above the position in which the work is fed to the machine, and has bolted or otherwise secured to its upper end, a supporting-plate C for the framework in which the operative parts of the machine are held in proper relation. This supporting framework consists principally of a transversely disposed bearing *a* for the drive-shaft *b* of the machine, and vertical bearings *c* for the vertically reciprocal tubular shaft *d*. The bore of bearings *c* is open to the bore of bearings *a* at about the centers of length thereof, to permit of the engagement of said vertical shaft by the drive-shaft, through the medium of a worm-gear *Y* splined on the tubular shaft *d* and a worm *X* keyed on drive-shaft *b* and located in a suitable chamber made in the transverse bearings *a* and engaging said worm-gear. This leaves the vertical shaft free to reciprocate longitudinally but imparts the revolving motion of the drive-shaft thereto.

80

Secured to and projecting laterally from a suitable external flat surface on the side of vertical bearings *c* is a bracket *D*. At about its center of length the horizontal portion of this bracket is provided with vertical bearings for a vertical spindle *e*, which bracket has its ends bent or curved downward and forms an arch for a magazine, comprising an annular side-wall *E*, and a circular table *G* on the lower end of the spindle *e*. This annular side-wall *E* has its lower edges *f* flanged inward and beveled on their upper side, and the circular table *G*, which is secured to the spindle *e* in the same horizontal plane as said flanged edges *f*, is substantially concentric with said edges but removed therefrom a distance corresponding to the diameter of the barrel of the screws to be deposited therein, and the circumferential edge of the table is likewise beveled on its upper side corresponding to the bevel of the flanged edges *f*. The spindle *e* is driven at a slow speed by means of a worm gear *e'* thereon, which latter is engaged by a worm *F* on the adjacent extended end of the drive-shaft *b*. As stated, table *G* is of

95

100

105

such diameter that its edges are opposite but separated from the edge of the flange f of the annular wall, so that a circular space or runway x is left between them, into which the barrels of the screws supplied to the magazine fall, and are suspended by reason of the heads thereof resting on the beveled edges of the table and flange. As said table slowly revolves the screws are moved around to a point nearest the vertical bearings c , where they are dropped, one by one, through a suitable recess in the flange f into a tubular chute g , which latter extends down from the rim of the magazine to the chuck, as will hereinafter be more fully described.

Secured to the rear portion of the wall E is a suitable bearing h for a substantially horizontal shaft h' , whose forward end extends beyond its bearings above the magazine, and is driven by a worm gear h^2 , which is actuated by the same worm F that actuates spindle e . Between this worm gear h^2 and the adjacent end of the bearings of shaft h' , the latter has a circular brush h^3 secured thereto, the diameter of the periphery of the wires composing which is such that said wires brush back any surplus screws that may be carried forward by the revolving table, and allow only those to pass which are suspended by their heads in the annular runway.

From a point directly under shaft h' to a point beyond the discharge opening of the magazine I prefer to cover over the runway x by a segmental bar M that fits inside and is secured against the inner surface of the annular wall E just above the flange f thereof. This prevents the screws after they pass the brush, from crowding each other to such an extent that they would climb upward. I also secure to the underside of the rim, in such position as to be disposed about an equal distance on either side of the discharge opening of the magazine, a short segmental plate J , which latter is provided with a vertical slot j' , in the portion thereof on the side of the discharge opening toward which the screws approach, to permit of the passage of the pendent screw-threaded portions of the screws until the same is over the discharge opening. The discharge opening is made by recessing the under edge of the annular wall E including a portion of the flange f , on the side of the magazine, preferably, nearest the vertical bearings c of the machine. This recess is occupied by a trip k that consists of a flat piece of metal fulcrumed mediate its ends by a screw, which latter assists in securing plate J to the wall of the magazine. The trip k is arranged in a tangential direction to the outer circumference of the annular wall, and the portion thereof extending from its fulcrum into the recess in the under edge of the said wall E , is

slightly more than twice the width of that portion of the trip projecting in the opposite direction from its fulcrum. This broader part or head of the trip is kept pressing inward by a spring m placed between its opposite end and the adjacent outer circumference of the wall E , as shown. The inner edge of the head portion of the trip partially laps over and forms a yielding section of the outer wall of the runway and is beveled on its upper side. As the screws move toward the position where they will be discharged from the magazine they are engaged and retarded by the trip and come into position under a vertically reciprocating plunger 2 , one after another in close order. The lower end of this plunger moves through a suitable guide-opening O in the segmental bar M , and has a finger 3 extending straight downward from its lower extremity through the annular runway and forms a stop for the screws in the same, at a point immediately over the discharge opening. In this position the screw is suspended between the table and the trip, and when the plunger moves downward it engages the screw and forces it downward and thereby makes trip K yield outward to permit the screw to pass downward into the chute g . Chute g extends downward in a laterally inclined direction toward, and has its lower end secured in an alining stub 4 projecting from the adjacent side of a tubular extension 5 , whose upper end is flanged and secured to and depending from the bushing 6 in the lower end of the vertical bearing c . The part of the extension 5 above the plane of stub 4 may have elongated openings in its side, if desired; the part below said stub has its bore reduced and occupied by a filler tube 8 , that is held in place by a set-screw 9 , and has its lower end extended below the lower extremity of the chuck and, preferably, provided with a circumferential flange to strengthen it. This tube 8 is cut away to permit the screw from the chute g to enter its bore, and its portion between its lower flanged edges and the lower end of the chuck, is provided with diametrically opposite openings 10—10, 115 preferably, in a transaxial plane substantially at right angles to that intersecting chute g . Below the plane of the stub 4 the chuck is flattened, and the narrower sides or edges of this flattened portion are 120 grooved longitudinally, commencing at about the plane of the stub and extending to the lower end of the chuck, to provide seats for the corresponding jaws 12, 12. These jaws consist of elongated strips of 125 metal, that are fulcrumed about their centers of length, and each have a coil spring 13 placed between its upper end and the side of the chuck to keep their lower ends, normally pressing in toward each other. 130

The lower ends of these jaws are bent toward each other, and are adapted to enter openings 10 of the tube and their extremities approach near each other. Corresponding semi-funnel-shaped grooves 15^a are made in the opposing faces of these extremities, and when a screw is fed to tube 8, the screw-threaded point thereof enters this funnel-shaped opening between the extremities of the jaws, and said jaws will be forced apart as the screw is forced down between them by the bit 26, but will hold said screw straight and steady while it is being driven into the work.

The shaft *d* is tubular and its upper end extends above the vertical bearing *c* a suitable distance and is surrounded by the sleeve 15. Both above and below this sleeve said shaft *d* is screw-threaded, and has nuts 16 and 17 thereon below said sleeve, and a collar 18 above the same, by means of which the sleeve is prevented from moving longitudinally independent of the shaft; and yet permits said shaft to revolve therein. Sleeve 15 is engaged at points diametrically opposite each other by the bifurcated forward ends of a horizontally disposed lever 19, which latter is fulcrumed between the upper ends of the links 20, and has its rear end connected by the rod 21, to a suitable treadle, which I do not show in the drawings but which is of a common construction. The lower ends of the links 20 are pivotally connected to a vertical webbing 22, extending back from the vertical bearing *c* and connecting the same to the supporting-plate *C*, and the rear branch of the lever 19, is connected by the coil expansion spring 23, directly or indirectly to the plate *C*, and keep the forward end of the latter normally at the limit of its upward movement. When the foot is pressed upon the treadle, the forward end of the lever 19 moves the shaft *d* downward. The upper end of the collar 18 is flared or flanged circumferentially to provide a seat 24 in its upper end for a friction disk 25 of wood fiber or other suitable material. The bit 26 is removably secured in the lower end of a vertical shaft 7, which latter is of such diameter and length that it extends up through the bore of shaft *d*, and beyond the upper end thereof a suitable distance. The bit extends down through the tubular extension 5 a suitable distance, and, when shaft *d* is moved downward through the medium of the lever 19, will engage the screw and screw it into the work. The upper portion of shaft 7, extends above the upper end of shaft *d*, and is provided with a friction-head 27, which latter consists of a cylindrical or other shaped boss having its lower end flanged circumferentially, and with the lower face thereof opposing the friction-disk 25 provided with an annular bead, which is, preferably, tri-

angular in cross section, and has its apex engaging said facing 25. The upper end of the shaft 7 is screw-threaded and is provided with gage-nuts 28, and between these nuts and the upper end of the friction-head, 70 said shaft is surrounded by a compressed coil spring 29. By tightening up the nuts 28 the pressure of the friction-head 27 against the friction-disk 25 of the collar 18 may be adjusted so that when the bit has 75 driven the screw into the work a sufficient distance, the resistance to the further progress of the screw will be so great that the head 27, and, consequently, shaft 7, which derives its motion from shaft *d* through 80 the medium of the head 27, will not revolve. Sleeve 15 is provided with a lateral arm 30, the extremity of which is provided with a suitable ring-shaped boss through the opening in which the upper end of plunger 85 2 freely passes. From this boss the plunger 2 extends down through a suitable guide-opening in the upper portion of the bracket *D*, and is provided with a longitudinally adjustable collar 32 below the guide-opening, 90 which determines the extent of its upward movement, and is also provided a suitable distance above the guide-opening in said bracket with an adjustable collar 33, between which and the upper end of the 95 bracket said plunger is provided with a compressed coil spring 39, that assists in keeping the plunger normally at the limit of its upward movement. At first the downward movement of shaft *d* does not affect 100 plunger 2, but when it has traveled sufficiently for the boss on the end of arm 30 to engage collar 33, the plunger will be moved downward thereby far enough to force the screw in the runway immediately under it 105 into chute *g*. Collar 33 is adjusted so that the plunger 2, does not move downward until shaft *d* and bit 7 are nearly at the limit of their downward movement, and so that it is only during the withdrawal movement of the bit that the screw is fed to the screw-holding chuck.

What I claim as new is:—

1. A screw driving machine comprising means for holding the screw, a bit, a longitudinally reciprocal vertical shaft, frictional devices through the medium of which said bit derives motion from said shaft pressing axially of said bit to secure the desired friction and mounted to share the longitudinal 115 movement of the bit so that the amount of friction is not affected by said longitudinal movement of the bit, and devices for feeding screws to said screw-holding means.
2. In a screw driving machine, the combination with a screw-holding chuck, and a magazine for feeding screws to said chuck one at a time, of a longitudinally reciprocal revoluble shaft, a bit alining with and extending beyond the same, and frictional 120 130

means pressing axially of the bit to secure the desired friction and mounted to share the longitudinal movement of the bit so that the amount of friction is not affected by said 5 longitudinal movement of the bit.

3. In a screw driving machine, the combination with a screw holding chuck, and a magazine from which screws are fed to said chuck one at a time, of a longitudinally reciprocal revoluble shaft, a bit extending through and beyond the same, and spring actuated frictional devices pressing axially of the bit to secure the desired friction and mounted to share the longitudinal movement 10 of the bit so that the amount of friction is not affected by said longitudinal movement of the bit.

4. In a screw driving machine, the combination with a screw holding chuck, and a magazine for feeding screws to said chuck one at a time, of a longitudinally reciprocal revoluble shaft, an inner shaft extending through the same, a bit alining and revoluble with said inner shaft and extending 25 beyond the latter, and frictional means for imparting the motion of said tubular shaft to said inner shaft and bit, said means pressing axially of the bit to secure the desired friction and mounted to share the longitudinal movement of the bit so that the amount of friction is not affected by said 30 longitudinal movement of the bit.

5. In a screw driving machine, the combination with a screw holding chuck, and a magazine from which screws are fed to said chuck one at a time, of a longitudinally reciprocal revoluble tubular shaft, an inner shaft extending through the same, a bit alining and revoluble with said inner shaft and 35 extending beyond the same, and spring actuated frictional devices through the medium of which the revoluble motion of said tubular shaft is imparted to said inner shaft and bit, said means pressing axially of the bit to 40 secure the desired friction and mounted to share the longitudinal movement of the bit so that the amount of friction is not affected by said 45 longitudinal movement of the bit.

6. A screw driving machine comprising a screw-holding device, a revoluble bit reciprocal longitudinally independent of its 50 bearings, a magazine, and a longitudinally reciprocal plunger for ejecting the screws one at a time from said magazine which has a movement delayed so as to coincide with the 55 finish of the downward movement of the bit.

7. A screw driving machine comprising a screw-holding device, a revoluble bit reciprocal longitudinally independent of its 60 bearings, a magazine, and a longitudinally reciprocal automatically returnable plunger for ejecting the screws one at a time from said magazine which has a movement de-

layed so as to coincide with the finish of the downward movement of the bit.

8. A screw driving machine comprising a screw-holding device, a revoluble bit reciprocal longitudinally independent of its bearings, a longitudinally reciprocal shaft 70 from which said bit derives motion, a magazine, and a vertically reciprocal plunger for ejecting the screws from the magazine one at a time; said plunger being actuated by said shaft, and having a movement delayed 75 so as to coincide with the finish of the downward movement of the bit.

9. A screw driving machine comprising a screw-holding device, a revoluble bit reciprocal longitudinally independent of its 80 bearings, a longitudinally reciprocal shaft from which said bit derives motion, a magazine, and a vertically reciprocal plunger for ejecting the screws from the magazine one at a time, means operatively connecting said 85 shaft and plunger, which latter has a movement delayed so as to coincide with the finish of the downward movement of the bit.

10. A screw driving machine comprising 90 a screw-holding device, a revoluble bit reciprocal longitudinally independent of its bearings, a longitudinally reciprocal shaft from which said bit derives motion, a magazine, and a longitudinally reciprocal plunger 95 for ejecting the screws from the magazine one at a time, adjustable means operatively connecting said shaft and plunger, which latter has a movement delayed so as to coincide with the finish of the downward 100 movement of the bit.

11. In a screw driving machine, the combination with a magazine, a longitudinally reciprocal plunger, and a chute into which said plunger discharges screws from said 105 magazine one at a time, of a suitable tubular chuck alining with the bit, opposing jaws pivoted to the sides of said chuck having their lower ends normally pressing toward each other, and suitable grooves in their 110 opposing extremities, and a revoluble bit reciprocal independent of its bearings.

12. In a screw driving machine, the combination with a suitable magazine, a longitudinally reciprocal plunger, and a chute into 115 which said plunger discharges screws from said magazine one at a time, of a suitable tubular chuck alining with the bit, jaws pivoted to the sides of said chuck having their lower ends normally pressed toward each 120 other, and having suitable grooves in their opposing extremities, a tubular filler in the bore of said chuck having an opening in its side communicating with the bore of said chute, and having openings adjacent to its 125 lower extremity through which the lower ends of said jaws enter, and a revoluble bit reciprocal independent of its bearings.

13. In a screw driving machine, the combination with a screw holding chuck, and a magazine from which said screws are supplied to said chuck one at a time, of a vertically longitudinally revolving tubular shaft having its upper end screw-threaded, a collar engaging the same the upper end of which is flanged circumferentially, a revolvable bit reciprocal longitudinally through said tubular shaft and independent of its bearings, nuts on the upper screw-threaded end of said bit, a head splined on said bit engaging the flanged end of said collar and a spring interposed between said nuts and head. 40
14. In a screw driving machine, the combination with a screw holding chuck, and a magazine from which said screws are supplied to said chuck one at a time, of a longitudinally reciprocal revolving tubular shaft, a collar surrounding and secured to the upper end of the same having its upper end flanged circumferentially and provided with a depressed seat in its upper face, a disk in 45 said seat, a rotatable bit reciprocal longitudinally through said tubular shaft independent of its bearings, gage-nuts on the upper end thereof, a head on said bit engaging the said disk, and a spring interposed between said nuts and head. 50
15. In a screw driving machine, the combination with a screw holding chuck, and a magazine from which said screws are supplied to said chuck one at a time, of a longitudinally reciprocal revolving tubular shaft, a collar surrounding and secured to the upper end of the same the upper end of which is flanged circumferentially and has a depressed seat in its upper face, a disk in 55 said
16. In a screw driving machine the combination with a suitable magazine, a chuck for holding the screw to be driven, and a revolvable bit reciprocal independent of its bearings, of a longitudinally reciprocal revolvable shaft through which motion is imparted to said bit, a sleeve loose on the upper end of said shaft but movable longitudinally therewith and having a laterally projecting arm, and a plunger the upper end of which is adjustably secured to said arm, and the lower end of which is adapted to engage the screws in the runway of the magazine and 60 expel them one at a time. 65
17. A screw driving machine comprising a screw-holding device, a revolvable bit reciprocal independent of its bearings, a longitudinally reciprocal shaft from which said bit derives motion, a magazine, and a reciprocal plunger for ejecting the screws from the magazine one at a time, and adjustable means operatively connecting said shaft and plunger. 70

In testimony whereof I have hereunto set my hand and seal this 15 day of March, A. D., 1906.
